CLAIM

The ornamental design for a combined spray bottle and cap, as shown and described.

DESCRIPTION

FIG. 1 is a perspective view of a combined spray bottle and cap showing my new design;

FIG. 2 is a front elevational view thereof;

FIG. 3 is a left side elevational view thereof, the right side being a mirror image;

FIG. 4 is a rear elevational view thereof;

FIG. 5 is a top plan view thereof;

FIG. 6 is a bottom plan view thereof;

FIG. 7 is an exploded front elevational view thereof;

FIG. 8 is a left side elevational view of FIG. 7, the right side being a mirror image;

FIG. 9 is a rear elevational view of FIG. 7; and,

FIG. 10 is a top plan view of the bottle shown without the cap for clarity of illustration.

FIG. 1FIG. 4FIG. 3FIG. 2FIG. 5FIG. 6FIG. 10FIG. 7FIG. 8FIG. 9
